UNITED STATES PATENT OFFICE!

FRANS KANKKONEN, OF ASTORIA, OREGON.

COLLAPSIBLE BOAT.

1,067,659.

Specification of Letters Patent.

Patented July 15, 1913.

Application filed September 23, 1912. Serial No. 721,901.

To all whom it may concern:

Be it known that I, FRANS KANKKONEN, a citizen of the United States, residing at Astoria, in the county of Clatsop and State of Oregon, have invented certain new and useful Improvements in Collapsible Boats; and I do declare the following to be a full, clear, and exact description of the invention, such as will enable others skilled in the art 10 to which it appertains to make and use the same.

This invention relates to boats, and more especially to those which are flexible so that they may be folded or collapsed; and the 15 object of the same is to produce a life saving boat capable of being collapsed to a small compass so that it may be carried on ship-board ready for instant use in case of emergency.

20 The invention consists in the specific details of construction whereby this idea is carried out, all as hereinafter more fully described and claimed and as shown in the drawings wherein—

25 Figure 1 is a side elevation and Fig. 2 is a plan view of this improved boat ready for use; and Fig. 3 is a central longitudinal sectional view of the same; Figs. 4 and 5 are enlarged cross sections on the lines 4—4 and 30 5—5 of Fig. 3; Fig. 6 is an enlarged side elevation of the distending mechanism, with the hub of the intermediate spider shown in section, and Fig. 7 is a cross section on the line 7—7 of Fig. 6; Fig. 8 is a vertical section through the right-hand spider shown 35 in Fig. 6. Fig. 9 is a detail partly in section showing the connection of the outer end of one brace member with a rib, and Fig. 10 is a cross section on the line 10—10 of Fig. 9. 40 Fig. 11 is an enlarged section detail of the floating valve and the means for admitting air to the air-tight compartments.

45 This improved boat is built with a perfectly straight keel 1 covered with iron or other metal so as to protect the material of the keel and afford ballast for the boat, and the stems 2 and 3 at the bow and stern are connected with the extremities of said keel by knuckle joints or hinges 4 so that they 50 may be turned outward slightly in collapsing the boat but may not turn inward farther than as shown in Fig. 1, because when they turn in that position the knuckle hinges are closed. Overlying the keel and 55 extending throughout the length of the same is a board 5 somewhat wider than the keel

and constituting a sill, and above this board in turn stands the keelson 6 braced to the board by means of brass knees 7; and when the stems 2 and 3 are turned in to the position shown in Fig. 1 they lie against the extremities of said sill and keelson and are braced thereby. Each stem carries the outer leaves 8 of a number of hinges, whose inner leaves 9 are secured to the extremities of 65 longitudinal ribs 10 whereof four are shown on each side of the boat in the present instance, although there may be a greater or lesser number. The gunwale 11 is likewise hinged to the upper ends of the stems 2 and 3 and may carry rowlocks 12 as shown. When the boat is distended said ribs are bowed outward and the gunwale more than any rib, and all these members are depressed at about their midlength; and it follows that 70 75 the pintles of the hinges connecting their extremities with the stems will at this time stand on different lines from what they will stand when the boat is collapsed and all the longitudinal members are straight. But 80 under these conditions the stems are turned outward around their hinges 4, and the pintles of all the hinges connecting the longitudinal members with said stems stand vertical. The seats 13 rest in the present instance on the uppermost ribs when the boat is distended. It is obvious that when the boat is distended and the seats are in place, they serve to hold it distended or to assist 85 90 in holding it distended.

95 Mounted in eye-bolts 20 which rise from the keelson is a telescopic shaft consisting of a solid rod 21 having teeth 22 in its upper edge, and a tubular section 23 embracing said rod and having a slot or interruption 24 95 overlying the teeth. One end of the rod is connected as at 25 with one extremity of the keelson and extends thence into the end of the tubular section, but the latter slides through the eye-bolts for a purpose which 100 will presently appear. Secured upon said section 23 at various points (at three points as shown herein) are spiders 26 each having a beveled periphery 27 provided with a number of hemispherical sockets 28, and secured 105 to said periphery in any suitable way as by bolts 29 is a beveled ring 30 having hemispherical sockets 31 adapted to register with those in the periphery 27 and pierced with holes 32 leading into these sockets. In each 110 of the latter is mounted a spherical head or ball 33 carried by a shank 34 which projects

through said hole 32 and is connected with a tube section 35; and into the other end of this section passes a rod 36 rendered adjustable therein by means of a nut 37—the whole 5 making up a brace member having a ball-and-socket connection with the spider at its inner end and a suitable connection at its outer end with one of the ribs or one of the gunwales. In Fig. 9 are shown the details 10 of this attachment, wherein the outer end of the rod 36 is formed into an eye 40 loosely embracing and linked into a ring or staple 41 secured to the rib. In a boat of about the 15 proportions shown in the drawings, there will be three such spiders and sets of rings, and it is obvious that when the tube section 23 is moved longitudinally upon the rod 21 the outer ends of the braces will cause the 20 ribs and gunwales to bow outwardly, the proper degree of bowing being induced by making the braces of proper length as will be clearly understood by any one versed in shipbuilding.

The means which is preferably employed 25 for adjusting the distension of this collapsible boat consists in providing one of the spiders with a sleeve 50 surrounding the tube section 23, and pivoting to said sleeve at 51 a lever 52 whose lower end carries a pawl 53 30 projecting downward through the interruption 24 in the tubular section 23 and engaging the teeth 22 in the solid section 21; and the sleeve also carries a retaining pawl 54 engaging the same teeth—these pawls being 35 pressed into active position by means of springs 55 and 56 as best seen in Fig. 6. With this construction it will be obvious that when the lever 52 is moved on its pivot in one direction, the pawl 53 engaging the 40 toothed rod 21 causes the tubular section 23 to be moved along upon said rod, and the retaining pawl 54 holds these telescopic members while the lever is being moved in the opposite direction for a new bite of its pawl. 45 As above explained, the movement of the tube section carries all the spiders in a proper direction to throw the braces outward and distend the ribs and gunwales; and when the boat is to be again collapsed the 50 pawls are raised out of engagement with the teeth in the rod 21, after which the tube section 23 with all its spiders may be allowed to move in the opposite direction so that the outer ends of the braces are drawn inward 55 as desired.

The body of this boat is made of heavy 60 canvas or other suitable flexible material, rendered waterproof and air-tight in any suitable manner, and applied in such a way 65 that it will exclude the water and will retain the air in its air-compartments described below. This covering 60 is secured to one gunwale 11, passes thence downward outside the several ribs 10, under the sill 5 and over 70 the keel 1, and upward over the ribs 10 at

the other side to the opposite gunwale 11 to which its other edge is secured; and it extends from the stem 2 to the stern 3 and is secured to both in any suitable manner not necessary to illustrate. At the bow and stern 70 ends of the boat the canvas cover is continued over the top into decks 61 which are raised and distended by the provision of proper braces in the endmost series as shown, and the ridge-pole 62 of each deck passes 75 under the highest point of the canvas and is hinged at its outer end at 63 to the stem, while its inner end is connected by an eye-bolt 64 with the keelson and keel so as to prevent it from being elevated too high 80 when the boat is raised by the davit-hooks that are engaged with the eyes of these bolts.

Buoyancy is imparted to this boat by providing it with air-compartments at both ends and under its decks, and each compartment is produced by the provision of a cross partition 70 of canvas which is secured at its upper edge to the deck covering 61 and at its side edges to the body covering 60. By preference I also form another compartment 90 along the bottom of the boat, which is produced by stretching a canvas sheet 73 from the third rib upward from the keel on one side, downward under the second rib, thence across and over the keelson at the point 74, 95 under the second rib of the other side, and upward to the third rib at this side of the boat; and at suitable points this false bottom of canvas may be sustained by means of hooks 75 depending from certain of the 100 seats and engaging screw eyes 75' whose shanks pass through the canvas sheet, and are seated in longitudinal wooden strips 76 located within this bottom air-compartment. The endmost compartments may be provided 105 with internally threaded collars or nipples 77, and the intermediate compartment with a like nipple 78, and with all of them are detachably connected air-tight screw couplings 79, each at the inner end of a short 110 section 80 of hose having at its outer end a hollow rubber ball 81, as best seen in Fig. 11. In the upper side of each ball is an opening 82 forming a seat for a valve 83 which closes upwardly by means of a light 115 spring 84. The construction shown in Fig. 11 is only illustrative of one manner of carrying out this detail of construction. This view also shows in dotted lines how the hose-coupling 79 could be detached from 120 the nipple 77 and a smaller hose 85 passed through the opening in the nipple 77 and allowed to hang within the compartment, so that a pump 88 at the outer end of this 125 smaller hose could be used to pump water out of the compartment in case the latter should leak. Or, an air pump might be attached to the nipple 77, and the compartment forcibly blown up. The idea is that, when the ship sinks quickly or unexpectedly, 130

there is but little time and much confusion in which to launch the life boats. If one of my improved construction is thrown overboard or washed from the deck, two sailors could open it even while swimming in the water—one of them manipulating the lever 52 so as to distend the sides of the boat and cause the air-compartments to suck in air through the valves 83 which are above the water level by reason of the floating ball 81, and the other sailor putting in the seats as soon as the sides of the boat have been distended sufficiently. In folding this craft for storage upon the deck, the valves 10 are opened so as to permit the deflation of the air compartment, the pawls 53 and 54 raised, and the tube section 23 allowed to slip along on the rod 21 so that the various braces permit the ribs and gunwales to 15 straighten out as their hinge-connections with the stems at the extremities of the keel will permit. In doing this the sides of the boat approach each other and the stems swing outward around their hinges 4, but 20 the ridge-poles 62 of the endmost air-compartments can not rise on account of the eye bolts which hold them down. The seats are lifted off the ribs which sustain them and hooked to the keelson as above described, and in its collapsed condition the 25 entire boat will occupy a space of about thirty inches in diameter, its length being a little over 30 feet. When occasion arises for the use of the boat its framework is 30 distended in the manner above described, the eye bolts connected with the davit hooks, and the craft let over the ship's side and 35 down into the water, unless the accident occurs so quickly that the life boats are thrown overboard or washed overboard as above 40 described. After the air-tight compartments are filled with air, the use of the life boat follows that of any other life-saving craft, and need not be amplified here. An air- 45 pump might be connected with the nipples and air pumped into the compartments. I would say that a thirty foot boat having a beam of about eight feet will carry from thirty to fifty passengers, and yet would be 50 so light that but two people would be required to lift it or to launch it. Obviously it is no heavier when the air compartments are inflated than when they are deflated. I have described my preferred form of ball 55 and socket connection between the braces and the spiders, but it is clear that other flexible connections might be used at this point, possibly somewhat similar to the connections at the outer ends of the braces as 60 also described. I consider the nuts 37 within the length of the braces important because their use permits the adjustment of such length so that the braces when distended will hold out the ribs properly and 65 the nuts can be turned to make them do

so. While I have shown but three spiders and sets of ribs in the drawings, it is obvious that a greater or lesser number might be employed according to the size of the boat.

Having thus described my invention, what 70 I claim is;

1. In a collapsible boat, the combination with a rigid keel, a rigid keelson mounted thereon, substantially upright stems hinged to the extremities of said keel and adapted 75 to lie against the extremities of said keelson, and longitudinal flexible members connecting these stems; of a flexible covering inclosing the framework, a longitudinally movable member mounted on the keelson, and a plurality of distenders carried by said member and each including a spider and a series of braces loosely connected at their inner ends with the spider and at their outer ends with 80 said flexible members, for the purpose set 85 forth.

2. In a collapsible boat, the combination with a framework including a rigid keel, upright stems hinged to the extremities thereof, and longitudinal flexible members 90 connecting said stems; of a flexible covering inclosing the framework, and a distending device including a rod connected with said keel at one end of the latter, a tube section slidably mounted on the rod, means for moving it longitudinally thereon at will, spiders secured to the tube section, and oblique braces flexibly connected at their inner extremities to said spiders and at their outer extremities to said flexible members, for the 95 purpose set forth.

3. In a collapsible boat, the combination with a framework including a rigid keel, upright stems hinged to the extremities thereof, and longitudinal flexible members 105 connecting said stems; of a flexible covering inclosing the framework, and a distending device including a rod connected with said keel at one end of the latter, a tube section slidably mounted on the rod, means for moving it longitudinally thereon at will, spiders secured to said tube section and having beveled peripheries provided with hemispherical sockets, beveled rings surrounding said peripheries and themselves provided with registering sockets and with holes opening from the same, balls fitting 110 said sockets and having shanks projecting loosely through said holes, and braces connected at their inner ends with said shanks 115 and loosely connected at their outer ends with said flexible members, for the purpose set forth.

4. In a collapsible boat, the combination with a framework including a rigid keel, 125 upright stems hinged to the extremities thereof, and longitudinal flexible members connecting said stems; of a flexible covering inclosing the framework, and a distending device including a rod connected with said 130

keel at one end of the latter, a tube section 5
slidably mounted on the rod, means for
moving it longitudinally thereon at will,
spiders secured to said tube section, and
braces loosely connected at their inner ends
10 to said spiders and at their outer ends to
said flexible members, and each brace com-
posed of an inner tubular section and an
outer solid section telescoping thereinto, and
a nut on the solid section against the end
15 of the tubular section, for the purpose set
forth.

5. In a collapsible boat, the combination
with a skeleton framework including a rigid
15 keel, substantially upright stems pivoted to
the extremities thereof, and longitudinal
flexible members loosely connecting said
stems; of a flexible covering inclosing the
framework, and a distending device includ-
20 ing a rod connected at one end with said
keel and having ratchet teeth, a tube section
slidably mounted on said rod and hav-
ing a longitudinal slot alining with its teeth,
spiders on said tube section, braces loosely
25 connected at their inner ends with said
spiders and at their outer ends with said
flexible members, a sleeve connected with
one spider, a lever pivoted in the sleeve,
and a pawl carried by the lever and pro-
30 jecting through said slot and engaging said
teeth, for the purpose set forth.

6. In a collapsible boat, the combination
with a skeleton framework including a rigid
35 keel, substantially upright stems pivoted to
the extremities thereof, and longitudinal
flexible members loosely connecting said
stems; of a flexible covering inclosing the
framework, and a distending device includ-
40 ing a rod connected at one end with said
keel and having ratchet teeth, a tube section
slidably mounted on said rod and having a
longitudinal slot alining with its teeth,
spiders on said tube section, braces loosely
45 connected at their inner ends with said
spiders and at their outer ends with said
flexible members, a sleeve secured to one of said
spiders, a lever pivoted within the sleeve, a
pawl pivoted to the inner end of the lever
50 and projecting through said slot and en-
gaging said teeth, a spring for throwing this
pawl normally into engagement with said
teeth, a retaining pawl also pivoted to the
sleeve and projecting through the slot, and
55 a spring for throwing the tip of this pawl
normally into engagement with said teeth,
for the purpose set forth.

7. In a collapsible boat, the combination
with a keel having an upright stem at each
60 end, a hinge connection between each stem
and the keel, a number of longitudinal mem-
bers flexibly connected at their extremities
with said stems, ridge poles each hinged at
its outer end to one of the stems, and an

eye bolt connecting its inner end with the
keel; of a flexible cover inclosing said frame- 65
work and secured at its edges to the upper-
most of said flexible members, the cover of
the ends of the craft being carried over said
ridge poles to form decks at those points,
and a distending device including a longi- 70
tudinally movable rod, a plurality of spiders
thereon, braces flexibly connected at their
inner ends with said spiders and at their
outer ends with said flexible members, and
additional braces in the endmost spiders 75
for distending the covering forming said
decks.

8. In a collapsible boat, the combination
with a keel having an upright stem at each
end, a hinge connection between each stem 80
and the keel, a number of longitudinal mem-
bers flexibly connected at their extremities
with said stems, ridge poles each hinged at
its outer end to one of the stems, and an eye
bolt connecting its inner end with the keel; 85
of a flexible cover inclosing said framework
and secured at its edges to the uppermost
of said flexible members, the cover at the
ends of the craft being carried over said
ridge poles to form decks at those points, 90
and a distending device including a longi-
tudinally movable rod, a plurality of spiders
thereon, braces flexibly connected at their in-
ner ends with said spiders and at their outer
ends with said flexible members, braces from 95
the endmost spiders for distending the cov-
ering forming said decks, and at the inner
end of each ridge pole a cross partition of
flexible material connected with the inner
edges of the deck covering and carried 100
thence downward into the hull and produc-
ing an air-compartment at the end of the
boat.

9. In a life boat, the combination with
the keel, longitudinal ribs, and upright 105
stems; of a canvas covering inclosing the
framework, the keelson secured upon the
keel, the cross seats, and a canvas sheet ex-
tending from the third rib downward within
the covering and under the second rib 110
thence across over the keelson, under the
second rib at the other side and upward to
the third rib so as to produce an air space
along the bottom of the boat, strips extend-
ing longitudinally beneath this canvas sheet, 115
upright hooks leading from certain of the
seats downward, and screw eyes whose
shanks pass through the canvas and engage
with said strips.

In testimony whereof I have hereunto set 120
my hand in presence of two subscribing wit-
nesses.

FRANS KANKKONEN.
